ELLIPSOGRAPH COMPASS

Filed Sept. 12, 1929

UNITED STATES PATENT OFFICE

WALDO G. BENNETT, OF SCAPPOOSE, OREGON

ELLIPSOGRAPH COMPASS

Application filed September 12, 1929. Serial No. 392,166.

The present invention is directed to improvements in compasses.

The primary object of the invention is to provide an instrument of this character so constructed that ellipses of various sizes can be quickly and accurately drawn.

Another object of the invention is to provide an instrument of this kind so constructed that circles may be described, the instrument being capable of being adjusted for forming ellipses.

A further object of the invention is to provide an instrument of this nature so constructed that a complete ellipse may be drawn upon imparting to the instrument a complete rotation or twist.

With these and other objects in view, this invention resides in the novel features of construction, formation, combination and arrangement of parts to be hereinafter more fully described, claimed and illustrated in the accompanying drawings, in which:

Figure 1 is a perspective view of the device.

Figure 2 is an enlarged detail sectional view through the casing.

Figure 3 is a sectional view on the line 3—3 of Figure 1.

Referring to the drawings, 1 designates the main leg of the device which consists of aligned upper and lower sections 2 and 3, respectively, the opposed ends of which are spaced and are provided, respectively, with lateral arms 4 and 5. A pair of upper and lower links 6 and 7 are employed and have their inner ends secured to the ends of the arms 4 and 5 by screws 8 which serve to hold the arms and links engaged with sufficient friction to prevent accidental movement but permit relative adjustment when desired.

Pivotedly mounted between the outer ends of the links 6 and 7 is a cylinder 9 having a transverse opening 10 formed therein and into which extends a set screw 11 which is adapted to engage the rod 12 slidable in the opening 10, said rod being connected with the leg 13. The upper end of the leg 13 has pivotally connected thereto, as at 14, a connector 15, which consists of telescopically connected sections 16 and 17, there being a coil spring 18 interposed between the upper

end of the section 16 and filler 19 mounted in the upper end of the section 17, the latter being of hollow formation to allow for the telescopic connection.

The filler 19 is pivotally connected, as at 20, to the bar 21 fixed to the head 22, said head having a knurled knob 23 carried thereby to facilitate rotation.

The head 22 is aligned with the section 2 of the leg 1 and has fixed thereto a beveled gear 24. A similar gear 25 is fixed to the upper end of the section 2 of said leg. A casing 26 is provided which consists of separable complementary sections 27 adapted to engage in the grooves 28 and 29 formed, respectively, in the head 22 and section 2. The sections 27 of the casing are held together by bolts 30.

Extending into the casing is a shaft 31 which is journaled in the bearings 32 provided in the casing. Loosely mounted on the shaft are beveled pinions 33 which mesh with the gears 24 and 25, as clearly shown in Figure 2 of the drawings. The shaft is provided with an arm 34 in order that the shaft can be held against rotation with one hand while the other hand is employed for rotating the head 22 through the medium of the knob 23.

The section 3 of the leg 1 is provided with a steel point 35 while the leg 13 carries the head 36 in which is mounted a lead point 37.

The spring 18 will tend to urge the section 16 downwardly, thus holding the lead point 37 in contact with the paper.

When it is desired to form an ellipse, the links 6 and 7 are adjusted for the proper size, whereupon the knob 34 is held firmly in one hand while the knob 23 is twirled with the other hand and owing to the differential action of the gears 24 and 25 and the pinions 33, an ellipse can be easily and accurately formed.

Of course, when it is desired to merely draw a circle, the knob 23 is turned synchronously with the shaft 31.

In drawing an ellipse, it will be noted that the leg 1 will rotate in one direction while the connector 15 and leg 13 will rotate in a reverse direction, this being, of course, due to

the presence of the intermeshing gears 24 and 25 and pinions 33.

From the foregoing, it is thought that the 5 operation and many advantages of the herein described invention will be apparent to those skilled in the art without further description, and it will be understood that various changes in the size, shape, proportions, and minor details of construction may be 10 resorted to without departing from the spirit or sacrificing any of the advantages of the invention.

What is claimed is:

1. A compass of the class described comprising a main leg consisting of upper and lower sections, a head, a connector pivotally connected with the head, a second leg pivotally connected with the connector, links connected with the upper and lower sections 20 of the main leg, a rod carried by the second leg and adjustably connected with the links, and a gear assembly between the head and main leg sections to rotate the main leg and second leg in reverse directions.

25 2. A compass of the class described comprising a main leg consisting of upper and lower sections, a head, gears fixed to the opposed ends of the head and upper section of the leg, a shaft extending between the gears, 30 pinions loose upon the shaft and meshing with the gears, a second leg, a connector between the second leg and head, arms carried by the opposed ends of the upper and lower sections of the main leg, links connected with 35 the arms, a rod projecting from said second leg, and means for adjustably connecting the rod with the links.

3. A compass of the class described comprising a main leg consisting of upper and 40 lower sections having arms carried by their opposed ends, a head alined with the main leg sections, a second leg pivotally connected with the head, means for adjustably connecting the second leg with the arms, a differential gear assembly between the head and main leg operating to rotate the main leg and second leg in reverse directions.

4. A compass comprising a main leg 45 formed of a pair of alined sections, a second leg, a head, a differential gearing between the head and one of the sections of the main leg, connecting means between the second leg and the head, and connecting means between said second leg and said pair of alined sections of the main leg.

5. A compass comprising a main leg 50 formed of a pair of alined sections, a second leg, a head, a differential gearing between the head and one of the sections of the main leg, means pivotally connecting the second leg with the head, and a yieldable connection between said second leg and said pair of alined sections of the main leg.

6. A compass comprising a main leg 55 60 formed of a pair of alined sections, a head,

a casing forming connecting means between the head and one of the sections of the leg, a shaft passing between the head and said section of the leg and mounted in the casing and projecting to form a handle, a differential gearing between said section of the leg, said head and said shaft, a second leg, means pivotally connecting the second leg with said head, and a yieldable connection between said second leg and said alined sections of the main leg.

In testimony whereof I affix my signature.

WALDO G. BENNETT. [L. S.]
